METHOD OF PREPARING GLASS PANELS

Application filed February 25, 1930. Serial No. 431,314.

This invention relates to a method of treating glass surfaces so that advertising matter may be effectively displayed thereon.

An object of the invention is the production 5 of a glass display panel having an inner surface carrying advertising matter and a background and an outer surface treated in a novel manner so that it will not emit glare and high lights which render indistinguishable the advertising matter carried by the inner surface and observable through the treated outer surface.

Another object is to provide an efficient practical and inexpensive method for the 15 manufacture of glass display panels of the above type.

These and other objects are attained by the method and means described herein and illustrated in the accompanying drawing, in 20 which:

Figs. 1 and 2 illustrate a plan view and a cross-sectional view, respectively, of a panel to be treated.

Figs. 3 to 6 inclusive illustrate the various 25 steps of the process for treating the panel.

Fig. 7 is a cross-sectional view of the completed panel.

Fig. 8 is a greatly enlarged cross-sectional 30 view of the panel showing its condition after the etching treatment.

Display panels of the general type disclosed herein are in common usage on the illuminated globes of gasoline dispensing pumps, for displaying the trade names of the 35 various kinds of gasoline on sale. The display panels of the present invention are adapted for such use, but it is to be understood that the method disclosed herein may be applied also to the manufacture of spherical display globes and to globes of other shapes.

Some of the display panels in common usage have a ground or etched outer surface with advertising matter painted or otherwise 45 applied to said outer surface. Others have a transparent but glossy outer surface through which may be observed the advertising matter painted or otherwise applied to the rear or inner surface. The advertising matter of the first mentioned type of panel

is more easily read because of the fact that glare or high lights are eliminated by removal of the gloss or finish from the outer surface, but such panels are objectionable because of the fact that atmospheric action soon 55 removes or partially removes the exposed painted advertisement. The second mentioned type of panel is objectionable for the reason that the advertising matter thereon is rendered indistinguishable by glare or high 60 lights when viewed from certain angles. This glare or high light is caused chiefly by reflection of light from an extraneous source, such as daylight or surrounding artificial illumination. By treating display panels in 65 the manner disclosed herein, the glare or high lights of the outer surface are reduced sufficiently to render the advertising matter readily distinguishable, the outer surface however remaining transparent so that the advertising matter may be applied to the inner surface and observed through the outer surface. The improved panel also may be illuminated from the inside during the night 70 season, as is common practice.

The method of treating the panel is as follows. A preferably circular sheet 11 of transparent glass (Figs. 1 and 2) has one of its surfaces 10 exposed to a fine but brief spray 9 (Fig. 3) of paint or other suitable material which will afford some resistance to the action of dilute hydrofluoric or other acid suitable for etching glass. The sprayed panel then is immersed in a bath of said acid (Fig. 4) which acts freely upon the under or inner 80 surface 12 of the panel but which attacks the upper or coated surface 10 only in the minute spaces between the minute globules of paint or coating material on said surface. After removal of the panel from the acid bath and 85 after washing to check further action of the acid, the surface 10 is found to differ materially from surface 12 in that its projections and depressions, caused by non-uniform acid action, are very pronounced compared with 90 those of the uncoated face 12. Because of the protective coating, however, there is actually less etched surface on face 10 than on the unprotected face 12, as is readily understood. The etching on face 10 is insufficient to 95 100

terially affect the original transparency of said face.

After washing and drying of the panel, the advertising matter 13 is painted upon or otherwise applied to the completely etched inner face 12, after which a background 14 of contrasting paint or other suitable substance is applied to the face 12. The background substance or paint may cover the advertising matter, as indicated.

The next operation is that of firing the panel to set the paint and shape the panel. This is accomplished by placing the panel upon a concave or dished mold 15, (Fig. 6) and subjecting the panel and mold to an intense heat which is sufficient to cause the panel to soften and sag, of its own weight, assuming the dished shape of the mold. Upon cooling, the panel is removed from the mold in the condition indicated in Fig. 7, the advertising matter being on the concave face 12, the convex face 10 carrying the minute spaced etched areas as above explained.

Because of the character of surface 10 after acid etching in the presence of minute paint globules as above described, the face 10 is not rendered smooth by the firing operation, as it would be if etched in the absence of such protective globules. The minute protective globules insure the formation of comparatively large spaced projections or humps on the surface 10 between the acid etched areas, as is disclosed by microscopic inspection. These projections are sufficiently large and substantial to prevent their collapse or flattening out during the firing operation. As stated before, the transparency of surface 10 is not materially affected by the treatment, but said surface thereby is rendered substantially free from the objectionable highlights and glare occasioned by light from extraneous sources.

The acid bath used in the process preferably is a solution of hydrofluoric acid and water, in which solution the panel is immersed for a period of several minutes. The strength of the solution and the period of immersion are related factors and must be taken into consideration for attainment of the desired result, as is well known. If the bath is rather strong, the panels should remain therein in a shorter period of time than would be necessary for a weaker bath, to attain the same results.

By the foregoing method, a glass advertising display panel is produced, the advertising matter of which is readily distinguishable at all angles of vision because of the absence of glare and high-lights, and which affords protection from the elements for the advertising matter. The advertising matter, although applied to the concave or rear face of the panel, appears to be on the convex or exposed face of the panel. It is to be understood that the panel manufactured in accord-

ance with the invention does not require interior illumination, as do ground glass panels having advertising matter or letters painted upon the interior unexposed glossy face thereof.

What is claimed is:

1. The method of treating glass objects having opposite faces, said method consisting of spraying finely atomized acid resist upon one of the faces whereby to provide on said face numerous minute particles for resisting acid action, immersing the coated object in an etching acid bath capable of attacking glass surfaces, removing the etched object from the bath, and applying decorative matter to the other face thereof. 70

2. The method of treating glass objects having opposite faces, said method consisting of applying to one of the faces numerous minute substantially uniformly spaced particles of acid resist, immersing the coated object in an etching acid bath capable of attacking glass surfaces, removing the etched object from the bath, applying decorative matter to the other face thereof, and firing the decorated object to bake the decorative matter on said face. 85

3. The method of treating glass objects having opposite faces, said method consisting of applying to one of the faces numerous minute substantially uniformly spaced particles of acid resist, immersing the coated object in a etching acid bath capable of attacking glass surfaces, removing the etched object from the bath and washing said object to remove the coating material and to check the action of the acid, applying decorative matter to the other face of the object, and firing the decorated object to bake the decorative matter on said face. 90

4. The method of treating glass objects having opposite faces, said method consisting of applying to one of the faces numerous minute substantially uniformly spaced particles of acid resist, immersing the coated object in an etching acid bath capable of attacking glass surfaces, removing the etched object from the bath and washing said object to remove the coating material and to check the action of the acid, applying decorative matter to the other face of the object, applying background material to said other face, and firing the decorated object to bake the decorative matter and the background material on the said face. 105

5. The method of treating glass objects having opposite faces, said method consisting of applying to one of the faces numerous minute substantially uniformly spaced particles of acid resist, immersing the coated object in an etching acid bath capable of attacking glass surfaces, removing the etched object from the bath and washing to check the action of the acid, applying decorative matter to the other face of the object, super- 115

posing the object upon a shaping device, and firing the superposed object for baking the decorative matter on said face and for semi-liquefying the object thereby causing the 5 object to sag into the shaping device and to assume the interior contour thereof.

6. The method of treating glass objects having opposite faces, said method consisting of applying to one of the faces numerous 10 minute substantially uniformly spaced particles of acid resist, immersing the coated object in an etching acid bath capable of attacking glass surfaces, removing the etched object from the bath and washing to check 15 the action of the acid, applying decorative matter to the other face of the object, superposing the object upon a shaping device, with the decorative matter uppermost, and firing the superposed object for baking the 20 decorative matter on said face and for semi-liquefying the object thereby causing the object to sag into the shaping device and to assume the interior contour thereof.

7. The method of treating glass objects 25 having opposite faces, said method consisting of applying to one of the faces numerous minute substantially uniformly spaced particles of acid resist, immersing the coated object in an etching acid bath capable of attacking 30 glass surfaces, removing the etched object from the bath and washing to check the action of the acid, applying decorative matter to the other face of the object, applying background material to said face, 35 superposing the object upon a concave shaping device, with the decorative matter uppermost, and firing the superposed object and semi-liquefying said object thereby causing it to sag into the concavity of the shaping 40 device and to assume the concave shape thereof.

8. The method of treating glass panels having opposite faces, said method consisting of spraying finely atomized paint upon 45 one of the surfaces whereby to provide on said surface numerous minute particles for resisting acid action, immersing the sprayed panel in an etching acid bath capable of attacking glass surfaces, removing the etched 50 panel from the bath and washing same to check the action of the acid, applying decorative matter to the other face of the panel, superposing the panel upon a shaping device with the decorative matter uppermost, and 55 heating the panel sufficiently to semi-liquefy the panel and cause it to assume the shape of the shaping device.

In testimony whereof, I have hereunto subscribed my name this 21 day of February, 60 1930.

GUSTAVE F. MATTMAN.
